SCAFFOLD MACHINE

Peter Hoitsma, Paterson, N. J.

Application November 26, 1935, Serial No. 51,586

3 Claims. (Cl. 304—29)

In my Patent No. 1,441,806 there is set forth a scaffold machine comprising, with a load-carrying member to flank an upright and having means to engage the latter normally free to move upwardly but not downwardly on the upright, lifting means including a lever pivotally connected with said member and movable up and down and means in which the lever is fulcrumed having a gripper engaging the upright and normally free to move upwardly but not downwardly thereon, said lever having means to bear laterally on the upright. To raise the load-carrying member, the lever is depressed, being then supported by the third-named means and so lifting said member, at the end of which movement the first-named means obtains a fresh grip on the upright. To descend, the lever is held elevated to obtain thereby a slip grip on the upright while its gripper is held retracted (as by hand) and the first-named means is caused (as by the operator's foot) to disengage the upright. In practice, it has been found that there is no danger of such a mechanism getting out of control and unduly falling during the attempt to descend provided that when said first-named means is depressed the operator, holding the gripper retracted, also holds the lever in gripping relation to the upright, releasing the first-named means or the gripper when the desired descent has been accomplished. Nevertheless, it is desirable, especially when the mechanism is used by timid operators, to eliminate any hazard in this respect, and this indicates the principal object of the present invention.

In the drawing,

Fig. 1 is a side elevation of an upright and apparatus thereon constructed in accordance with the present invention;

Fig. 2 is an elevation as viewed from the right in Fig. 1;

Fig. 3 is a fragmentary isometric view of the lower end of the apparatus;

Fig. 4 is a section on a horizontal line immediately above the element 17 in Fig. 1; and

Fig. 5 is a fragmentary section on line 5, Fig. 4.

Let 1 be an upright, as a 4x4 of wood, to rest on the ground. The load-carrying member comprises the following parts: an angle-iron element 2 having an inverted U-shaped form; an arm 3 also having a U-shaped form and bolted to member 2, as at 4; angle-iron braces 5 (only one being shown) bolted at 6—6 to member 2 and arm 3; a pair of plates 7 secured by bolt 4 and a bolt 8 to the upper end of member 2, the plates straddling the upright and one of them having a rigid upstanding extension 9 in the form of a plate

having its upper edge curled to provide a bearing 9a and a removable pin 7a spanning the plates at the side of the upright remote from element 2. The means by which said load-carrying member engages the upright consists of a shackle comprising a U-shaped member 10 which is pivoted to the lower end of member 2 on a bolt 11 and straddles the upright and has two bars 12 spanning the same, one at each side of the upright, being fixed against rotation in (though one may be removable from) the member 10 and each being square in cross-section and presenting an edge to the upright; the shackle is normally urged to the position shown in Fig. 1, so that both bars press against the upright, by a spring 13 coiled about the bolt 11 and arranged to engage members 2 and 10, as shown in Fig. 3. The arm 3 is incidentally shown capable of folding on the bolt 6 which joins the arm and brace 5, when extended its pivoted or folding part being adapted to bear against a bolt 14.

So much is not materially different from my said patented construction. As for the lifting means:

A shackle or gripper, arranged above the load-carrying member and embracing the upright, is constructed as follows: 15 is a U-shaped member which straddles the upright. At one side of the upright it is spanned by a square bar 16 fixed against rotation therein and presenting an edge to the upright. At the other side of the upright there spans and is journaled in said member a bar 17. The portion 17a of the bar between and of shorter length than the spacing of the extremities of member 15 is square in cross-section and twisted so as to form a steeply pitched helix whereas its end portions 17b are reduced and form trunnions which are journaled in said extremities and one of which may be prolonged and bent to form a crank 17c; one of said trunnions is for a part of its length, as at 17x, square in cross-section to fit a corresponding square hole 15a (Fig. 5) in the member 15, thus forming in effect a spline. Pivoted on a bolt 18 outward of the bar 16 is a U-shaped link member 19 whose extremities carry a bolt 20 which affords a fulcrum for the lever 21 and may bear against the upright, the shorter arm of the lever being pivotally connected with the load-carrying member by a pin 22 which is removably received in the curl 9a of the extension 9 of its plate 7, and the longer arm of the lever preferably having a U-shaped stirrup 23. A spring 24 is coiled about the bolt 18 and bears against member 15 and link member 19, tending to maintain them alined

with each other or so that member 15 assumes the position shown in Figs. 1 and 2.

It will be understood that the upright and the described mechanism thereon are duplicated and 5 that the planking to support the workmen is arranged on the arms 3. The upper shackle and the lever in the present instance project at right angles with respect to arm 3 and when the entire 10 equipment comprising the duplicated uprights and mechanism, with the planking, is assembled the levers are preferably arranged so that each projects toward the other upright so as to be in 15 convenient reach of the workmen.

Operation.—The load is of course normally 15 supported by the lower shackle, held in the position of Figs. 1 and 2 with its bars 12 bighting into the wood of the upright. To cause the mechanism to rise the lever is depressed by the operator's foot applied to its stirrup 23, the load-carrying member, with the lower shackle, sliding up 20 on the upright until the lever reaches its downward limit, whereupon said member remains supported by the shackle. To cause it to rise another stage, the lever is depressed and the above 25 operation repeated.

To descend the operator sits on the platform or 30 planking and with his foot releases the lower shackle, leaving the load supported by the upper shackle or gripper. He then turns the bar 17 35 by means of its handle 17c in the direction to cause said bar (which is in effect a roller) to roll down the upright, such action tending to release the grip of the gripper on the upright incident to the action of spring 24 and the load. In this way the upper shackle or gripper, carrying the 40 load, creeps down the upright.

As indicated, the bar 17 is in effect a roller and whatever shape its portion 17a may have I 45 find in practice that, when the upper shackle or gripper is under load, the elements 16 and 17 obtain a grip on the upright of such character that it requires effort, additional to that incident to the load, to turn the element 17, as by its handle 17c. However, if the bar is shaped as described, 50 or so as to present flutes, as 17y, helically developed around its axis and steeply pitched, all danger of its turning merely under the weight of the load is completely prevented and still it requires very little effort on the part of the operator to turn it by means of its handle.

If the operator desires additional assurance of safety when the mechanism is stationary or during rise, element 17 can be shifted lengthwise until it becomes splined with member 15 by its square portion 17x engaging in the square hole 5 15a, so that it is thus positively locked to member 15 against rotation.

Having thus fully described my invention what I claim is:

1. In combination, with an upright and with a load-carrying member having releasable means to grip the upright, a lever pivotally connected with said member and means in which the lever is fulcrumed including a member embracing, and having means to engage one vertical face of, the 15 upright and a roller journaled in the latter member in transverse relation to and bearing against the opposite face of the upright and having a handle by which to rotate such roller, the portion of the roller which bears against the upright being polygonal in cross-section.

2. In combination, with an upright and with a load-carrying member having releasable means to grip the upright, a lever pivotally connected with said member and means in which the lever is fulcrumed including a member embracing, and having means to engage one vertical face of, the 25 upright and a roller journaled in the latter member in transverse relation to and bearing against the opposite face of the upright and having a 30 handle by which to rotate such roller, the portion of the roller which bears against the upright being polygonal in cross-section and twisted to present flutes helically developed around the 35 axis of the roller and steeply pitched.

3. In combination, with an upright and with a load-carrying member having releasable means to grip the upright, a lever pivotally connected with said member and means in which the lever is fulcrumed including a member embracing, and 40 having means to engage one vertical face of, the upright and a roller journaled in the latter member in transverse relation to and bearing against the opposite face of the upright and having a handle by which to rotate such roller, said 45 roller being movable axially in the latter member and the roller and such member having means to form a spline connection between them when the roller is so moved.

PETER HOITSMA. 50
